UNITED STATES PATENT OFFICE.

CASPAR BLUMER, OF PHILADELPHIA, PENNSYLVANIA.

ROLL-LOCATING DEVICE.

1,231,479.

Specification of Letters Patent. Patented June 26, 1917.

Application filed August 24, 1916. Serial No. 116,646.

To all whom it may concern:

Be it known that I, CASPAR BLUMER, a citizen of the United States, residing in Philadelphia, Pennsylvania, have invented 5 a Roll-Locating Device, of which the following is a specification.

As will be understood by those skilled in the art of printing ornamental designs in a number of colors by the use of rolls or cylinders, it is of the utmost importance that each 10 of the print rollers shall be placed in the machine with its pattern or design occupying a predetermined and definite position with regard to other parts of the machine 15 as well as to the pattern on the paper or other web already printed, and in accomplishing this result, much time and labor have hitherto been necessary.

One object of my invention therefore is 20 to provide a relatively simple, substantial and conveniently operative device whereby each of a succession of print rollers may be quickly and conveniently adjusted in the machine to bring its design into precisely the 25 position desired.

Another object of the invention is to provide a device which may be inexpensively applied to roll printing machines for the purpose of quickly and conveniently positioning print rolls both longitudinally and circumferentially in order to bring their patterns into a predetermined relation with regard to another part of the machine and hence to a previously printed pattern.

35 These objects and other advantageous ends I secure as hereinafter set forth, reference being had to the accompanying drawings, in which,

Figure 1 is a side elevation, partly in vertical section, illustrating the preferred form 40 of my invention; and

Fig. 2 is an end elevation of the apparatus shown in Fig. 1.

In the above drawings 1 represents a portion 45 of one of the side frames of a roll printing machine having a bearing portion 2 in which is journaled one end of the shaft 3 designed to support and rotate the successive print rollers. On this shaft is fixed a gear 50 wheel 4 which is driven at a suitable speed by means forming no part of this invention but including a toothed member meshing with it.

Threaded on the shaft 3 is an adjusting 55 nut or collar 5 having a tapering or conical extension 6 designed to fit into the opening

of a plate 7 set on one end of the print roller 8. Obviously the opposite end of said roller is supported upon a second nut similar to the nut 5—6 and the arrangement is such 60 that the rotation of either nut will cause it, by reason of its threaded portion, to move longitudinally of the shaft 3, so that the print roller 8 may be shifted longitudinally 65 of the shaft in either direction and clamped in any given position.

For predetermining the position in which each roll is to be set or clamped, I mount on the frame 1 a pair of parallel bars 9 and 10 on which are mounted three slides 11, 12 70 and 13. The first of these is provided with a thumb screw 14 whereby it may be rigidly clamped to the bar 10 in any given position and in addition it is provided with a guideway for the reception of a rod 15 which is 75 slidable thereon in a line at right angles to the bars 9 and 10. This rod has a stud or screw 16 projecting from it through a slot 17 in the guideway and on said stud is a thumb nut 18 whereby said rod may be 80 clamped in any adjusted position. The rod at its lower or inner end carries a head 19 which slidably guides a pointed pin or rod 20 movable in a line at right angles to said first rod and capable of being retained in position by a screw 21 passing through a slot 22 in said head and held in place by a thumb nut 23.

The gear 4 on the shaft 3 has set in its side or web portion, adjacent the print roll, a 90 small plug or block 24 having a conical recess designed to receive the similarly shaped end of the pin or rod 20.

The slide 13 has a set screw 25 whereby it may be rigidly clamped to the bar 10 and has rotatably mounted in it a threaded stud 26 which enters the slide 12, the arrangement being such that rotation of the stud moves the slide 12 upon the bars 9 and 10. Said slide is provided with a guideway for the reception of a pointed bar 27 and each of the print rolls 8 has set in its cylindrical surface a metal plug or block 28 whose outer face lies flush with said roll. In said face is a conical recess designed to receive the pointed end of the rod 27 which has set in it a stud 29 extending through a slot 30 in the slide 12. This has a thumb nut 31 whereby said rod 27 may be clamped in any given position.

In using my invention, the shaft 3 with the gear wheel 4 is mounted in place, with

the block 24 of said gear in that particular definite position relatively to the frame 1 which it is desired that said shaft as well as any other shaft having a similar gear wheel, 5 shall thereafter occupy. The slide 11 with the rod 15 and pointer 20 are then so adjusted that the end of said pointer enters and fits the recess in the plug 24 of said gear wheel, after which the nut 23 on the screw 10 21 as well as the nut 18 on the screw 16 are tightly set up so as to hold these parts in their adjusted positions.

The slides 13 and 12 are now moved upon the guide rods 10 and 9 until the latter 15 slide occupies a position with its rod 27 approximately in the radial line through the plug 28 of the print roll, which by adjusting the nuts 5 on the shaft 3 has been previously moved until the pattern upon its 20 surface occupied the relative position which it is desired the patterns on subsequent rolls shall occupy. The screw 25 is then set up, thus clamping said slide 13 rigidly in place, and with the thumb nut 31 loosened, the 25 screw 26 is so manipulated as to shift the slide 12 until the point of the rod 27 fits into the recess of the plug 28.

After the shaft 3 with the roll 8 has been removed and replaced by a second print roll 30 and its associated parts, the latter is first turned on its longitudinal axis until the pointer 20 may enter the recess of the plug 24 of the gear wheel 4 on said shaft. The roll 8 is then so adjusted by means of its 35 nuts 5 and is also so turned upon the shaft, that the pointer 27 may be caused to fit into the recess of the plug 28; which as well as the plug 24 of the gear wheels, occupies definite positions relatively to the pattern 40 on said rolls. As a result of this setting, when any gear wheel and roll have been brought to the positions relative to the pointers 20 and 27 shown in Fig. 1, the pattern of said roll occupies a predetermined 45 position relatively to the other parts of the machine and to the pattern to be printed.

Obviously the adjustments of any roll in order to obtain the above desired results may be quickly made with the utmost ease, 50 where hitherto it has been necessary to adjust such rolls merely by an experimental method which required considerable time and hard labor.

When it is desired to operate the machine, 55 the pointers 20 and 27 are withdrawn from the recesses in the blocks or plugs 24 and 28 by loosening their clamping screws 22 and 31 and withdrawing them to retracted positions in which they are clamped until 60 required in positioning another roll. With-

out departing from my invention the plugs may be omitted and the gear and roll be provided with holes or recesses designed to co-operate with the pointers as previously described. Moreover while I preferably use 65 holes or recesses to co-operate with the pointers in locating a roll, it is possible that in some cases marks such as crosses or circles may be substituted for such holes without departing from my invention.

70

I claim;—

1. The combination of a pointer; a print roll; a recessed plug set in said roll in a definite position with regard to the pattern on the roll; and means for adjusting the roll 75 to bring the recess of its plug into a predetermined position relatively to the pointer.

2. The combination of a pointer; a print roll; a recessed plug set substantially flush with the curved surface of said roll in a 80 definite position relatively to the pattern thereon; and means for adjusting the roll to bring the recess of the plug into line with the pointer.

3. The combination of a supporting 85 frame; a shaft rotatably mounted therein; a member mounted on the shaft and having a recess extending in a line parallel to the shaft; a slide adjustably mounted on the frame; with an independently adjustable 90 pointer carried by the slide in position to enter the recess of the member when the latter occupies a predetermined position.

4. The combination of a frame; a shaft rotatably mounted therein; a member 95 mounted on the shaft having a definitely placed recess extending parallel with the shaft; a guide member also parallel to the shaft; a slide adjustable on said guide member; a bar adjustably held to said slide and movable toward and from the shaft; with a pointer carried by said bar in position to co-operate with the recess of the shaft-carried member when the latter occupies a predetermined position.

5. The combination of a supporting frame including a guide; two slides movable on said guide; means for clamping one of the slides to the guide; means for adjustably connecting the second slide to the first slide; 110 a pointer carried by the second slide and movable in a line at right angles to that of the guide; a shaft rotatably mounted in the frame; a print roll on the shaft having a recess definitely placed with relation to its pattern; and means for adjusting the roll on the shaft to bring its recess into a position to be entered by the pointer.

CASPAR BLUMER.
